UNITED STATES PATENT OFFICE.

RUSSELL RUFFUS WATERMAN, OF UPLAND, CALIFORNIA.

AIRSHIP.

1,007,827.

Specification of Letters Patent. Patented Nov. 7, 1911.

Application filed July 6, 1910. Serial No. 570,676.

To all whom it may concern:

Be it known that I, RUSSELL R. WATERMAN, a citizen of the United States, residing at Upland, in the county of San Bernardino and State of California, have invented a new and useful Airship, of which the following is a specification.

This invention relates to air ships, and one of the main objects of the invention is to provide novel and efficient means for controlling the lateral balance.

Another object is to provide an improved form of main plane.

Another object is to provide for steering the machine when traveling on the ground by the same controlling device which steers the machine when in the air.

Another object is to provide a novel construction of vertical and horizontal rudders located at the front end of the machine.

Referring to the drawings: Figure 1 is a perspective view of the complete machine. Fig. 2 is a vertical cross section taken on line x^2-x^2 Fig. 6. Fig. 3 is a perspective, in detail, of the connection between the arm which operates the vertical rudder and the steering rod. Fig. 4 is a side elevation, partly in section, of the joint between the vertical posts which operate the planes, for regulating the lateral balance. Fig. 5 is a side view of the air ship. Fig. 6 is a plan view of the air ship. Fig. 7 is a perspective, in detail, of the planes which control the lateral balance and the mechanism for operating the same.

The main frame of the machine comprises two side bars 1 which extend fore and aft and which at the rear end are connected to a rear frame 2 and at the front end are connected to a front frame 3.

4 and 5 designate the respective upper and lower main planes, the upper one of which, as clearly shown in Fig. 1, is dished both longitudinally and laterally to present a convex surface at the top and a concave surface at the bottom. The bottom plane 5 is bent laterally but is straight longitudinally. Spars 6 project vertically between the planes 4 and 5 and braces 7 strengthen the construction. The purpose of the longitudinal curvature of the upper plane, which curvature is laterally of the longitudinal axis of the machine, is designed to minimize lateral unbalancing movements similar to

the action of a parachute, the natural tendency of the dished upper plane being to assume a horizontal position at a point above the center of greatest weight below that plane. Extending vertically and journaled in the rear frame 2 are posts 8 and 9. As clearly shown in detail in Figs. 4 and 7, the posts 8 and 9 are free to turn with respect to each other at their adjoining ends. The upper post 8 carries a vertical balancing plane 10 while the lower post 9 carries a vertical balancing plane 11, which, in the normal operation of the air ship, as it is moving straight ahead and does not become unbalanced laterally, stand parallel with each other fore and aft and parallel to the line of movement of the air ship. But if the air ship becomes unbalanced laterally such that one end of the main planes 4 and 5 tips down, the balancing planes 10 and 11 may be swung in opposite directions to each other so that their resistance against the air will act to restore the lateral balance of the air ship. Thus if the right hand end of the main planes 4 and 5 tips down, the upper balancing plane should be swung so that its forward edge moves to the left, while its after edge is moved to the right, while the lower balancing plane 11 should be adjusted in the opposite direction, that is, with its forward edge moved to the right and its after edge moved to the left. With the balancing planes 10 and 11 adjusted in this manner it is obvious that as the air ship advances the resistance of the air against the planes 10 and 11 will act to turn the air ship on its longitudinal axis in a counter-clockwise direction, thus lifting the right side and lowering the left side. The amount of angular movement to which the planes 10 and 11 should be adjusted to correct this unbalanced position of the air ship will obviously be proportioned to the speed of travel and the amount of lateral unbalancing which the air ship has taken. The mechanism which I provide for accomplishing this adjustment of the planes 10 and 11 consists of a foot lever 12 pivoted at 13 and having a rod 14 which extends from the right hand end of the foot lever 12 to an arm 15 which is rigidly secured to the post 9, while a rod 16 extends from the same point on the lever 12 to an arm 17 on the post 8. Thus the aviator in operating the

machine rests both of his feet against the foot lever 12. If the machine tips laterally clockwise he will correct this unbalanced condition by pushing with his left foot 5 which will cause the lever 12 to push both rods 14 and 16 to the rear, thereby swinging arms 15 and 17 rearwardly and thus turning the forward edge of the upper plane 10 to the left and the forward edge of the 10 lower plane 11 to the right, so that as the air ship moves along the air resistance will act against the upper planes 10 and 11 to turn the air ship counter-clockwise and restore it to the proper position desired by 15 the aviator. If the air ship becomes unbalanced laterally in a counter-clockwise direction, the aviator will correct this unbalanced condition by pushing with the right foot on the lever 12 which will pull both 20 rods 14 and 16 forwardly, thereby adjusting planes 10 and 11 into position opposite to that just described which will have the effect of turning the ship in a clockwise direction as it moves along. A cross bar 18 extends 25 between the side bars 1 of the main frame and is provided with a bearing 19 in which is journaled a steering rod 20, at the rear end of which is a steering wheel 21, the steering rod 20 being also slidable in 30 the bearing 19. The steering rod 20 near its front end passes slidably through a rock arm 22 shown in detail in Fig. 3, the steering rod 20 having a feather 23 which slides in a corresponding groove in 35 the arm 22 and causes the arm 22 to oscillate when the steering rod 20 is turned, at the same time permitting the steering rod 20 to be moved longitudinally through the arm 22, the latter being held from longitudinal movement by a bracket 24, the latter permitting the arm 22 to freely oscillate. Pivoted to the lower ends of the front frame 3 is a horizontal rudder 25, and pivoted to the upper ends of the frame 3 is a horizontal 40 rudder 26, both rudders 25 and 26 being connected together by four connections 27, so that the two rudders move in unison and are kept in parallelism. The two rudders are operated by sliding the steering rod 20 longitudinally, the front end of the steering rod 20 having a ball and socket joint 28 which is connected by a link 29 with a ball and socket joint 30 on the upper end of an arm 31 which projects up from the rudder 45 25 and is rigidly attached thereto, so that by pushing forward on the steering rod 20 the lower rudder 25 will have its front edge moved downwardly and its rear edge moved upwardly, and at the same time the connections 27 impart a similar movement to the upper rudder 26. By retracting the steering rod 20 the rudders 25 and 26 will be adjusted in the opposite direction which will result in giving an upward direction 50 of movement to the air ship, the downward

direction of movement being given to the air ship by pushing forward on the steering rod which depresses the front edges of rudders 25 and 26. Pivotally supported in the front frame 3 is a vertical rudder 32 which 70 has a cross arm 33, to each end of which a flexible connection 34 is attached, each connection 34 passing over a pulley 35 and being connected to a spring extension 36 which is connected to the arm 22, so that as the 75 steering rod 20 is turned in either direction, and the arm 22 turns therewith, the latter will act through the connections 36 and 34 to turn the cross arm 33 and vertical rudder 32. As the arm 22 moves in a plane at right 80 angles to the plane of movement of the cross arm 33 there is some difference in distance linearly between the connections on each side of the arm 22 and cross arm 33 when the arm 33 has been moved in either direction 85 from a central position, although when in central position the linear distance through each connection on each side is the same. In order to allow for this difference in distance, I provide the spring extensions 36. 90 Lateral steering is afforded by the vertical rudder 32. Thus by adjusting the rudder 32 so that its front edge is moved to the left, the air ship will be guided to the left, while if the front edge of the rudder 32 be 95 moved to the right the air ship will be guided to the right. 100 I provide wheels 37 which are supported by springs 38 under the main planes at the rear while at the front I provide a wheel 39 which is carried on a fork 40, the latter being pivoted to the lower end of a column 41 so that the fork 40 is capable of an oscillatory motion which allows the wheel 39 to ride over obstructions without imparting undue vibration or jolt to the air ship, a compression spring 42 being provided between the column 41 and a rod 43 which extends through the column 41 and is connected to the fork 40. The wheel 39 105 is thus cushioned with respect to the frame of the air ship, and in addition to the foregoing advantages which it possesses is also of great value in alighting, as, even though the wheel 39 strikes the ground with considerable force, the air ship will not be severely shaken as the greater force of the shock will be absorbed by the spring 42. 110

What I claim is:—

In an air ship, an upper main plane and 115 a lower main plane connected together, propelling mechanism therefor, a vertical shaft extending below the lower plane, and another vertical shaft extending concentrically with the first shaft through both main 120 planes, a balancing plane connected to the upper shaft above the upper plane, a balancing plane connected to the lower shaft below the lower plane, an arm projecting 125 from the upper shaft, an arm projecting 130

from the lower shaft in a direction opposite to the first arm when the two shafts are in a central angular position, a foot lever pivoted to swing in a horizontal plane, and a connection from each of said arms to substantially a single point on said foot lever.

In testimony whereof, I have hereunto

set my hand at Upland, California, this 27th day of June, 1910.

RUSSELL RUFFUS WATERMAN.
